UNITED STATES PATENT OFFICE

**ALEXANDER OBERHOFFKEN AND EARL M. BOWEN, OF ROCKFORD, ILLINOIS, ASSIGNEES
TO THE INGERSOLL MILLING MACHINE COMPANY, OF ROCKFORD, ILLINOIS, A COR-
PORATION OF ILLINOIS**

DESIGN FOR A MACHINE TOOL

Application filed November 3, 1930. Serial No. 37,526. Term of patent 7 years.

To all whom it may concern:

Be it known that we, ALEXANDER OBERHOFF-
KEN and EARL M. BOWEN, citizens of the
United States, residing at Rockford, in the
county of Winnebago and State of Illinois,
have invented a new and original Design for
Machine Tools, of which the following is a
specification, reference being had to the ac-
companying drawing, forming part thereof.

Figure 1 is a front perspective view of the
machine tool, showing our new design.

Figure 2 is a rear perspective view thereof,
on a reduced scale.

We claim:

The ornamental design for a machine tool
substantially as shown.

ALEXANDER OBERHOFFKEN.
EARL M. BOWEN.
